INVENTOR.
H. B. Hartman,

BY

ATTORNEY.

WITNESSES:-

UNITED STATES PATENT OFFICE.

HARRY BUXTON HARTMAN, OF SCOTTDALE, PENNSYLVANIA.

SAFETY RAZOR.

Application filed December 13, 1921. Serial No. 522,134.

To all whom it may concern:

Be it known that I, HARRY B. HARTMAN, a citizen of the United States, residing at Scottdale, in the county of Westmoreland 5 and State of Pennsylvania, have invented certain new and useful Improvements in Safety Razors, of which the following is a specification.

This invention relates to safety razors, and 10 more particularly to an improvement in a type wherein the blade carrier may be adjusted to various angles with reference to the handle.

To that end a primary object of the invention 15 is to provide a simple construction which may be easily and economically manufactured and readily manipulated and adjusted when in use. In the latter connection the invention contemplates means for expeditiously clamping the blade in place 20 and likewise removing the same.

Another object of the invention is to provide 25 a novel joint for permitting the blade carrier to be set at the desired shaving angle, the said joint comprising a minimum number of parts thereby facilitating the manufacture and assembly and at the same time insuring positive and reliable operation 30 when in use.

With the above and other objects in view 35 which will more readily appear as the nature of the invention is better understood, the same consists in the novel construction, combination, and arrangement of parts herein- after more fully described, illustrated and claimed.

A preferred and practical embodiment of 40 the invention is shown in the accompanying drawings, in which—

Figure 1 is a side elevation of the razor with the blade carrier disposed at right angles to the handle.

Figure 2 is a detail perspective view of the 45 rear blade carrier adjusted to an oblique angle with reference to the longitudinal axis of the handle.

Figure 3 is an enlarged cross sectional view 50 of the assembled blade carrier and handle.

Figure 4 is a plan view of the type of blade used in connection with the improved razor.

Figure 5 is a bottom plan view of the blade clamp.

Figure 6 is a vertical cross sectional view 55 taken on the line 6—6 of Figure 3.

Figure 7 is a vertical cross sectional view taken on the line 7—7 of Figure 3.

Similar reference numerals designate corresponding parts throughout the several figures of the drawings.

Referring to the accompanying drawings it will be observed that the present construction includes in its general organization a blade carrier 1 and handle H connected by 65 a novel knuckle joint J. The said blade carrier 1 is preferably transversely arched or convex in cross section, as shown in Figures 6 and 7 of the drawings, and is provided at opposite sides thereof with the 70 guard edges 2, while the central portion thereof is formed with a spring housing socket 3 opening at the top of the blade carrier and having the bottom wall 4.

At each side of the mouth of the socket 3, 75 the said blade carrier is also preferably formed with the lug receiving openings 5 which may be of the key hole type, the tail slot portions 6 being adapted to accommodate a special type of clamping lug, as will 80 hereinafter more fully appear. At the sides of the openings 5 opposite the slots the blade carrier may be provided with the cam abutments 7 for cooperating with the eccentric bearing edges 8 of the clamping lugs 9 carried by the blade clamp 10.

As will be observed from Figures 3 and 7, the said clamping lugs 9 are pivotally supported in the bearing lugs 11 carried by the underside of the clamp and the pivot 90 pins 9^a thereof are disposed transversely of the clamp whereby the lugs may be forced into operative relation with the abutments 7 on the blade carrier by swinging the head of the lug toward the socket thereof. Thus, 95 after the blade B is placed in position upon the carrier and the clamp moved in place by inserting the lugs through the openings 5, it will only be necessary to pinch or squeeze the heads of the lugs 9 toward each 100 other to effect the clamping of the blade B in place. By moving the lugs with greater or less force against the abutments 7, the edges of the blade may be raised or lowered

with reference to the guard 2 to give a light or close shave as desired. In other words, as the cam edges 8 of the lugs 9 are eccentric to the pivot axis 9^a, the clamping plate is drawn tighter as the lugs are shifted further through their arc of movement.

In connection with the lugs 9 it will be observed that the shanks thereof may be provided with an offset fin or rib portion X 10 adapted to pass through the tail slot portions 6 of the key-hole opening when the clamp is positioned with reference thereto. The purpose of this type of slot in the blade carrier as well as a similar type of slot B' in 15 the blade B is to require the use of a special blade. Frequently the use of inferior blades in connection with an otherwise satisfactory type of razor impairs the functioning of the razor itself and therefore it is desirable for 20 the manufacturer of the razor to make a special high grade blade which can be relied upon to give satisfaction in connection with a particular type of razor and so construct both blade and razor that only the intended 25 type of blade can be used.

Another feature of practical importance resides in the novel joint J which connects the blade carrier 1 with the handle H, and permits angular as well as circumferential 30 movement of the carrier with reference to said handle. This construction is clearly shown in Figures 2, 3 and 6 of the drawings from which it will be observed that the upper end of the handle may be provided 35 with the spaced jaws 12, the outer edges of which may be rounded as indicated at 13, to provide a true bearing in the seat 14 formed around the edge of the opening 4^a in the wall 4 of the socket 3. That is to 40 say, the said wall 4 is provided with a cup shaped seat 14 which receives the rounded edges of the jaws 12 so as to permit of a direct bearing engagement between the socket and the jaws without the necessity 45 of interposing a special type of washer between the socket and the handle. This construction not only eliminates one additional part which would otherwise be required, but at the same time provides a more satisfactory bearing between the socket and the 50 handle.

For the purpose of providing the desired frictional engagement between the blade carrier and the handle, a spring tensioned 55 eye-bolt 15 is employed. The loop 16 of this bolt is positioned between the jaws 12 of the handle and the opening 17 thereof receives the pivot pin 18 while the shank portion of said bolt projects through the 60 opening 4^a in the bottom wall 4 of the socket, and carries at its upper end a suitable spring abutment washer 19. Between this washer and the inside of the wall 4 of the socket 3 is arranged a suitable coil 65 spring 20 which is compressed by the washer

19 when the eye-bolt is pushed into position to receive the pivot pin 18, thereby placing the parts of the joint under sufficient tension to provide a relatively tight frictional engagement between the carrier handle 70 which will prevent accidental shifting of the blade carrier but permit of the same being readily moved to effect the desired "set" or adjustment.

When it is desired to remove the blade 75 from the carrier it is only necessary to shift the lugs 9 outwardly until they aline with the openings and slots in the blade carrier and blade. The clamp 10 may then be readily lifted to disengage the blade B and, when it is desired to again use the razor, the reversal of the operation described will effect the positioning of the blade while the shifting of the lugs 9 inwardly, as by the thumb and forefinger, will quickly clamp 85 the blade in position.

Without further description it is thought that the features and advantages of the present improvement will be readily apparent, and it will of course be understood 90 that changes in the form, proportion, and minor details of construction may be resorted to without departing from the spirit of the invention or scope of the appended 95 claims.

I claim:

1. A safety razor including a blade carrier having openings, a blade clamping member, jointed cam elements projecting from and carried by the blade clamp and 100 adapted to enter said openings in the carrier, and the ends of said cam elements being adapted to be shifted to engage with the carrier to lock the clamp thereto.

2. A safety razor including a blade carrier having openings, a blade clamp, offset lug portions carried by the underside of the blade clamp, cam lugs pivoted in said offset portions and, when alined therewith, adapted to be inserted through the openings 110 in the blade carrier and then shifted to engage with the carrier.

3. A safety razor including a blade carrier having openings, cam abutments arranged at the sides of said openings, a 115 blade clamp, and pivoted cam lugs carried by said clamp and adapted to pass through said openings and engage with the cam abutments on the carrier to lock the clamp and carrier together.

4. A safety razor including a blade carrier having a central spring housing socket provided with an opening and a bearing seat in one wall thereof, a handle having one end thereof formed to fit into said seat, a bolt 125 carried by the handle and projecting into said housing socket and constituting a vertical axis about which the socket rotates, and a spring for maintaining the seat portions of the socket in engagement with the handle. 130

5. A safety razor including a blade carrier formed with a spring housing socket provided with an opening and a bearing seat in one wall thereof, a handle having a 5 bifurcated end portion and formed to fit into said seat of the socket, a bolt pivoted in said bifurcated end of the handle and projecting into the housing, and a spring carried by the bolt within the housing for 10 yieldingly connecting the carrier and handle.

6. A safety razor including a blade carrier formed with a central spring housing socket provided with an opening and a bearing seat in one wall thereof, a handle 15 having spaced jaws whose outer edges are rounded to conform to the seat in one of the walls of the socket, and a coupling for connecting the carrier and handle consisting of an eye-bolt, a pivot pin for connecting 20 the eye-bolt with the jaws of the handle to thereby permit the shank of said bolt to remain at right angles to the handle, and said shank of the eye-bolt projecting into the 25 socket of the blade carrier, a spring abutment washer carried by the end of the shank

of the eye-bolt, and a spring confined between said washer and the wall of the socket having the bearing seat.

7. A safety razor including a guard member of transversely curved form, and having openings, a blade clamp corresponding in cross sectional form to the guard member, camming abutments formed on the guard member adjacent the openings, pivoted lugs carried by the blade clamp and 30 adapted to fit in the openings in the guard member, each of said lugs having a camming surface eccentric to the pivotal axis of the lug, whereby when the said faces of the lugs engage with the camming abutments the blade clamp is progressively 35 drawn toward the guard member to place the blade held between the guard and clamp under varying tension.

In testimony whereof I hereunto affix my 40 signature in the presence of two witnesses.

HARRY BUXTON HARTMAN.
